(57) **CLAIM**

The ornamental design for a dosimetry pouch, as shown and described.

DESCRIPTION

FIG. 1 is a perspective view of a dosimetry pouch with (i) a flap portion of the dosimetry pouch in an open (i.e., up) position, and (ii) straps on opposite sides of the pouch extending away from the pouch;

FIG. 2 is a side view of the dosimetry pouch shown in FIG. 1 as viewed from a right-hand side to a left-hand side of the dosimetry pouch shown in FIG. 1 with a flap portion of the dosimetry pouch in a closed (i.e., down) position;

FIG. 3 is a rear view of the dosimetry pouch shown in FIG. 1 with a flap portion of the dosimetry pouch in a closed (i.e., down) position;

FIG. 4 is a front view of the dosimetry pouch shown in FIG. 1 with a flap portion of the dosimetry pouch in a closed (i.e., down) position;

FIG. 5 is a top view of the dosimetry pouch shown in FIG. 1 as viewed from above the dosimetry pouch shown in FIG. 1 with a flap portion of the dosimetry pouch in a closed (i.e., down) position; and,

FIG. 6 is a bottom view of the dosimetry pouch shown in FIG. 1 as viewed from below the dosimetry pouch shown in FIG. 1 with a flap portion of the dosimetry pouch in a closed (i.e., down) position.

The broken line showing of portions of the dosimetry pouch in FIG. 3 is included for the purpose of illustrating environmental structure and forms no part of the claimed design.
